UNITED STATES PATENT OFFICE.

MORRIS KASSER AND JOSEPH B. KASSER, OF SAN FRANCISCO, CALIFORNIA.

BATHING-SUIT.

1,135,903.

Specification of Letters Patent. Patented Apr. 13, 1915.

Original application filed June 8, 1914, Serial No. 843,893. Divided and this application filed October 18, 1914. Serial No. 866,865.

To all whom it may concern:

Be it known that we, MORRIS KASSER and JOSEPH B. KASSER, citizens of the United States, and residents of the city and county 5 of San Francisco, State of California, have invented a new and useful Improvement in Bathing-Suits, of which the following is a specification.

Our invention relates to improved bathing 10 suits wherein the garment is provided with a series of inner inverted pockets adapted to contain a series of water-tight bags that may be inflated either before or after the wearer enters the water; and the object of 15 our invention is to provide a bathing suit having inflatable means detachably secured thereto, said means being adapted to be inflated by the wearer and thus render the bathing suit buoyant for the purpose of 20 initial instructions in swimming or in case of danger or emergency to the bather.

We accomplish these several features by means of the device disclosed in the drawings, forming a part of the present specification, wherein like characters of reference 25 are used to designate similar parts throughout the said specification and drawings, and in which—

Figure 1 is a view disclosing the improved 30 bathing suit, a portion of the garment being broken away in order to disclose the manner in which one of the inflatable bags is detachably secured within one side of the pockets; and Fig. 2 is a vertical sectional view of Fig. 1 disclosing the manner in 35 which the air tube is inclosed in an inner central channel in the front of the bathing garment.

Referring to the drawings, the numeral 1 40 is used to designate a bathing suit, having inner inverted pockets 2, the lower ends 3 of which are open, the said pockets being adapted to receive and retain an inflatable bag 4. Each bag 4 has a valve 5 secured to 45 the lower end thereof and from each valve 5 a flexible tube 6 leads to a central tube 7 inclosed within an inner central channel 8 in the front of the bathing suit 1. The upper end of the tube 7 extends slightly 50 above the neck of the bathing suit 1 in the front thereof and is arranged to be inserted in the wearer's mouth so that the bags 4 may be easily inflated thereby. In order to

retain the bags 4 within the pockets 2 we have provided the lower open ends 3 thereof 55 with suitable snap buttons 10.

The operation is as follows: Should a bather desire to inflate the pockets 2 he may easily do so by inserting the upper end 60 of the tube 7 in his mouth and blowing therein, which will inflate the said bags 4 in the pockets 2. If the bags 4 should leak the same may be easily kept inflated by continually blowing or exhaling into the tube 7. The valves 5 will prevent, under normal 65 conditions, the deflation of the bags 4. The bags 4 may be easily removed from the pockets 2, when it is desired to wash the garment or bathing suit 1, by unfastening the snap buttons 10 and removing the said 70 bags 4 from the said pockets 2 and the tube 7 from the central inferior channel 8 in the front of the bathing suit.

It is obvious from the foregoing that we have provided improved means for inflating 75 and rendering buoyant a bathing suit.

We are aware that the present state of the art discloses inflatable bags disposed in a person's wearing apparel. We, therefore, do not claim such a combination broadly as 80 our invention, but

what we do claim as new and desire to secure by Letters Patent is—

1. A bathing suit having inner inverted pockets on each side and a central inner channel in the front thereof; an inflatable bag detachably secured within each pocket; 85 a tube extending from the top of the garment through the central channel and to each bag; and a suitable valve in each bag 90 adapted to normally retain the air therein.

2. A bathing suit having inner inverted pockets on each side and a central inner channel in the front thereof; an inflatable bag detachably secured within each pocket; 95 a tube extending from the top of the garment through the central channel and to each bag; a suitable valve in each bag adapted to normally retain the air therein; and means adapted to retain the bags within the 100 pockets.

3. A bathing suit having inner inverted pockets in each side and a central channel in the front thereof; an inflatable bag de- 105 tachably secured within each pocket; a tube extending from the top of the garment

2
through the central channel and to each bag; a suitable valve within each bag adapted to normally retain the air therein; and suitable clasp buttons adapted to secure the lower sides of the pockets and to retain the bags therein.

In witness whereof we hereunto set our

signatures in the presence of two subscribing witnesses.

MORRIS KASSER.
JOSEPH B. KASSER.
